Primary Examiner — T Chase Nelson

Assistant Examiner — Sydney Margaret Parsley

(57) **CLAIM**

The ornamental design for a locking device for a ladder, as shown and described.

DESCRIPTION

1. Locking device for a ladder

1.1 : Perspective

1.2 : Perspective

1.3 : Front

1.4 : Back

1.5 : Left

1.6 : Right

1.7 : Top

1.8 : Bottom

1.9 : Perspective view shown in position of use

The parts and environmental structure shown by means of broken lines in the reproductions are not part of the claimed design.

1 Claim, 9 Drawing Sheets
